UNITED STATES PATENT OFFICE.

SIDNEY E. ANDERSON, OF BROOKLYN, NEW YORK, ASSIGNOR TO WESTERN ELECTRIC COMPANY, INCORPORATED, OF NEW YORK, N. Y., A CORPORATION OF NEW YORK.

VACUUM-TUBE CIRCUITS.

Application filed February 7, 1923. Serial No. 617,533.

To all whom it may concern:

Be it known that I, SIDNEY E. ANDERSON, a citizen of the United States, residing at Brooklyn, in the county of Kings,

5 State of New York, have invented certain new and useful Improvements in Vacuum-Tube Circuits, of which the following is a full, clear, concise, and exact description.

This invention relates to three-electrode 10 vacuum tube circuits and has for its object to stabilize the operation of vacuum tube circuits, employing a variable source of potential.

In certain uses of vacuum tubes where exact 15 adjustments are necessary, slow changes in a source of potential, if not correct, may give rise to series difficulties. It is also at times desirable to energize vacuum tubes with pulsating electromotive forces such, 20 for example, as are derived from rectified alternating currents and if the frequency of the pulsations are of the same order of magnitude as frequencies to be transmitted, interference will result.

25 The invention aims to provide for using variable electromotive forces for energizing the vacuum tube and without disturbing the proper operation of the circuit.

In accordance with the invention the variable 30 electromotive force is so connected that while one portion of its potential is applied between the cathode and anode of the vacuum tube, another portion of opposite phase and of a value one over the amplification factor of the tube times the anode potential is applied to the grid or control electrode.

As is well known, a potential applied to the grid is substantially equivalent to applying a potential to the anode of a value μ times the grid potential, where μ represents the amplification factor. The effect of the above arrangement is therefore that when the source of potential is changed, 45 equal and opposite effects are applied to the vacuum tube and no change in the space current results.

In case an appreciable normal space current is desired it is necessary to apply an additional fixed potential to the grid in order to permit space current to flow. For rectification or detection, however, normally zero space current may be desirable.

The invention will be more fully understood from the following detailed description and claims taken in connection with the accompanying drawing.

Referring to the drawing by reference numerals, the vacuum tube 1 comprises the usual filamentary cathode 2, grid or control 60 electrode 3 and anode 4. The associated circuit shown is one adapted for amplifying or detecting signals which are received through an input transformer 6 and transmitted through an output transformer 7. A 65 variable source of electromotive force 10 is connected across resistance path 12, the positive terminal of the resistance being connected to the anode 4 through the primary of transformer 7 and the negative terminal being connected to the grid through the secondary of transformer 6. The cathode is connected to the resistance 12 at a point dividing it into portions 12^a and 12^b, the values of which are so related to each 70 other and to the internal impedance of the vacuum tube that the potential drops there across have the values

$$\frac{E}{\mu+1} \text{ and } \frac{\mu E}{\mu+1}$$

80 respectively, where E is the value of source 10 and μ is the amplification factor of the tube. The variable source of electromotive 85 force 10 may be a battery subject to slow variations due to the charge and discharge cycle, as shown in the figure, or some form of rectifier which supplies a pulsating unidirectional current, or a generator, in which 90 case there is superimposed upon the constant electromotive force of the generator a pulsating component due to the interruption of the current during commutation.

Battery 14 may be in series with the grid 95 to determine the portion of the tube characteristic at which the tube will operate. Condensers 15 and 16 may be employed to provide paths of low impedance for alternating currents in the input and output circuits. 100 In case the condensers 15 and 16 are used, the impedance of condenser 16 should preferably be μ times the impedance of condenser 15.

As soon as a change in potential of the 105 source 10 produces an increase in anode-

cathode potential of e volts, this simultaneously makes the potential of the grid $\frac{e}{\mu}$ volts more negative. Since this change is 6 the equivalent of μ times

$$\left(\frac{-e}{\mu} \right)$$

volts in the plate circuit, it is seen that there 10 will be no change in the space current. Thus, the invention insures that the space current will remain essentially constant over a wide range of variations in the potential of source 10. The internal impedance of 15 tube 1 may be regarded as a constant resistance over a considerable range of voltages especially if resistances 12^a and 12^b are relatively small.

The range of voltages over which stable 20 operation may be obtained may be increased by including in the resistance 12^b a resistance having a positive coefficient of resistance such, for example, as iron or by including in the resistance 12^a a resistance 25 having a negative coefficient of resistance such, for example, as carbon or boron. This may be explained by the fact that the plate impedance of a vacuum tube decreases as the plate voltage increases, and therefore, 30 the plate current with increasing plate voltage increases at a greater rate than does the voltage. If the portion 12^b of the resistance is of some material whose resistance increases with temperature and therefore with 35 the voltage applied to its terminals, this increase in resistance may be adjusted so as to compensate for the decrease in plate impedance, the total impedance between the cathodes and anode thus remaining constant. 40 Similarly, if the portion 12^a of the resistance is composed of a material having a negative coefficient of resistance, and the plate voltage increases, the drop across 12^a decreases, and the decrease in the voltage applied to 45 the grid serves to compensate for the decreased plate impedance. If the resistance 12^a be made to have approximately the same resistance characteristic as that of the anode-cathode impedance, resistance 12^b may be 50 omitted.

While only one embodiment of the invention has been shown and described, it is obvious that the invention may assume other forms within the scope of the appended claims.

55 What is claimed is:

1. A vacuum tube translating device having a cathode, an anode, and a control electrode, a variable source of potential for energizing said device connected to said cathode, means for applying potentials of opposite phase and having a ratio of one over the amplification factor of said tube to said control electrode and said anode respectively, and means for impressing on said device voltage variations to be repeated. 60 65

2. A vacuum tube translating device having a cathode, an anode and a control electrode, a variable source of space current potential for said device, a resistance path connected across said source, connections from said path to said electrodes respectively at such points that the potential applied to said anode is opposite in phase and μ times the potential applied to said control electrode, and means for impressing on said device voltage variations to be repeated. 70

3. A vacuum tube translating device having a cathode, an anode and a control electrode, a variable source of space current potential for said device, a resistance path connected across said source, connections from said path to said electrodes respectively at such points that the potential applied to said anode is opposite in phase and μ times the potential applied to said control electrode, 80 an additional source of potential in series with said control electrode, and means for impressing on said device voltage variations to be repeated. 85

4. The method of controlling the space 90 current in a vacuum tube having a cathode, an anode, and a control electrode which comprises applying between said cathode and anode a variable potential, simultaneously applying between said cathode and control electrode a potential opposite in 95 phase and equal to

1

μ

times said first potential, and simultaneously 100 impressing on said vacuum tube potential variations to be transmitted thereby.

5. The method of operating a vacuum tube having a cathode, an anode and a control electrode, which comprises applying to 105 said control electrode and said anode respectively, two potentials derived from a common source and of such relative values that their combined effects on the space current are substantially zero, applying an additional potential to said control electrode, and simultaneously impressing on said vacuum tube potential variations to be transmitted 110 thereby.

6. The method of operating a vacuum 115 tube having a cathode, an anode and a control electrode, which comprises applying to said control electrode and said anode respectively, two potentials derived from a common source and of such relative values that 120 their combined effects on the space current are substantially zero, applying an additional potential to said control electrode, and simultaneously impressing on said vacuum tube potential variations to be transmitted 125 thereby.

In witness whereof, I hereunto subscribe my name this 30th day of January A. D., 1923.

SIDNEY E. ANDERSON.
